R. Van Velthouen

UNITED STATES PATENT OFFICE.

RICHARD VAN VELTHOVEN, OF PHILADELPHIA, PENNSYLVANIA, ASSIGNOR
TO WILLIAM W. HARDING.

IMPROVEMENT IN PHOTOGRAPHIC ALBUMS.

Specification forming part of Letters Patent No. 59,323, dated October 30, 1866.

To all whom it may concern:

Be it known that I, RICHARD VAN VELTHOVEN, of Philadelphia, in the State of Pennsylvania, have invented a new and useful Improvement in Photographic Albums; and I do hereby declare that the following is a full, clear, and exact description of the construction and operation of the same, reference being had to the annexed drawings, and to the letters of reference marked thereon.

The drawings represent two disconnected leaves of a photographic album, showing the slotted strips of parchment or other material by means of which the leaves are bound together.

This is an improvement on the invention for which Letters Patent were granted to J. H. Hazzard and myself on the 17th October, 1865, on reference to the specification and drawings of which patent it will be found that certain slots or openings, *a*, in the strips therein represented are formed by having pieces the size of the slots cut completely out of the strip.

My present improvement consists in providing these strips with slots which are formed by being cut only on three sides, forming a flap, which, in the binding of the leaves to-

gether, is turned under and secured to the edge of the under side (*i. e.*, the side opposite to that on which the strip is glued) of the album-leaves, as hereinafter described.

In the drawings, A and B represent two album-leaves, each of which is provided with its strip, C, of parchment or other material, as described in the specification of the above-mentioned Letters Patent. *a* represents the slots, which are cut on three sides, *x y z*, forming the flaps *b*, which are turned down over the edges of the album-leaves and glued to the leaves, as shown, thereby covering up the raw edges of the cards or pasteboards which form the leaves so far as the exposure of these edges would be occasioned by the slots.

The improvement adds strength and finish to the album.

Having thus described my invention, I claim and desire to secure by Letters Patent—

Forming one or more flaps, *b*, in the strips C, in the manner and for the purpose substantially as shown and described.

RD. VAN VELTHOVEN.
